CLAIM

The ornamental design for universal food container, as shown and described.

DESCRIPTION

FIG. 1 is a top isometric view of the universal food container showing my new design in a closed configuration.

FIG. 2 is a top view thereof.

FIG. 3 is a bottom view thereof, shown in a reduced scale.

FIG. 4 is a front elevation view thereof, the rear elevation view being a mirror image without the corner tabs.

FIG. 5 is a right side elevation view thereof, the left side elevation view being a mirror image thereto, shown in an enlarged scale.

FIG. 6 is a top isometric view of the lid shown separately for ease of illustration.

FIG. 7 is a top view of the lid thereof.

FIG. 8 is a bottom view of the lid thereof.

FIG. 9 is a front elevation view of the lid thereof, the rear elevation view being a mirror image without the corner tabs.

FIG. 10 is a right side elevation view of the lid thereof, the left side elevation view being a mirror image thereto, shown in an enlarged scale.

FIG. 11 is a top isometric view of the base shown separately for ease of illustration.

FIG. 12 is a top view of the base thereof.

FIG. 13 is a bottom view of the base thereof.

FIG. 14 is a front elevation view of the base thereof, the rear elevation view being a mirror image without the corner tabs; and,

FIG. 15 is a right side elevation view of the base thereof, the left side elevation view being a mirror image thereto, shown in an enlarged scale.
